[57] **CLAIM**

The ornamental design for a combined holder for a note pad and pen, as shown and described.

DESCRIPTION

FIG. 1 is a top, right front perspective view of a combined holder for a note pad and pen showing my new design;

FIG. 2 is a side elevational view thereof, the opposite side being a mirror image of that shown;

FIG. 3 is a top plan view thereof;

FIG. 4 is a bottom plan view thereof;

FIG. 5 is a rear elevational view thereof; and,

FIG. 6 is a front elevational view thereof.
